UNITED STATES PATENT OFFICE.

JOHN ROUNSEVILLE AND AUGUST BILMS, OF CUXHAVEN, GERMANY.

TIME-INDICATOR FOR TELEPHONES.

No. 876,493.

Specification of Letters Patent.

Patented Jan. 14, 1908.

Application filed July 9, 1906. Serial No. 325,428.

To all whom it may concern:

Be it known that we, JOHN ROUNSEVILLE, a citizen of Hamburg, and resident of Cuxhaven, in the Empire of Germany, hotel proprietor, and AUGUST BILMS, a subject of the King of Prussia, and resident of Cuxhaven, in the Empire of Germany, watchmaker, have invented a new or improved Time-Indicator for Telephones, of which the following is a specification.

10 The present invention relates to an improved time measuring device for telephone conversations, which causes an audible alarm, when the time for a conversation at a fixed fee approaches its end.

15 Special objects of the invention are to simplify and cheapen the construction and to render more efficient serviceable and durable in operation devices of the kind referred to.

20 With these ends in view the invention consists in the novel combination, arrangement and adaptation of parts, all as more fully hereinafter explained, shown in the accompanying drawings and then specifically set 25 out in the appended claim.

In the accompanying drawings Figure 1 illustrates a front elevation of the improved time measuring device, the dial plate being removed. Fig. 2 is a side elevation illustrating the internal construction. Fig. 3 illustrates the means for stopping the watch work. Fig. 4 is a part plan view of Fig. 3. Fig. 5 represents a front elevation of the improved time measuring device ready for use.

30 The telephone companies in the various countries have universally adopted the custom of charging the use of the long-distance telephone by time at certain fixed rates, the latter varying with the distance over which the conversation is conducted. This habit has led to considerable inconvenience especially when the person conversing has been put into communication with the second party by the agency of a private subscribers telephone. In this case the subscriber is generally unacquainted with the length of the conversations and fraudulent use of the telephone is frequently the result of the custom referred to. Hotel proprietors, restaurants, 45 and other public institutions have suffered largely through the want of a practical time measuring device, which avoids disputes and

which will not touch the feeling of sensitive customers when being produced on asking for the proper amount of the telephone conversation.

55 The present invention renders it possible to calculate the proper charge by reading off the time occupied in the conversation from a dial plate of a watch set in motion at the moment when communication is established between the two parties and when the conversation starts.

In carrying into practice the invention a watch work, preferably that of an alarm 65 clock, is deprived of the hour hand and the ordinary dial plate, and is fitted with a dial plate *a*, whose circumference is divided into 60 equal parts indicating 60 minutes. Assuming the unit of a long-distance conversation 70 allowed by the telephone company at a fixed fee to be 3 minutes, said divisions are noticeably marked on the dial as indicated in Fig. 5. Obviously the time intervals granted as a unit for conversations may be varied 75 and may be marked in accordance on the graduation of the dial plate.

The tubular shaft *c* carries in front of the dial plate *a* a fixed hand *e* pointing with its extremity *d* over the graduation *b* and being 80 driven by the watch work to mark the 60 minutes of an hour. Behind the dial plate *a* is fixed to the shaft *c* a wheel *f*, whose periphery is provided with 20 saw-tooth like incisions or serrations *g*, serving for causing an 85 audible alarm by setting free the alarm work of the device, when the end of the time unit approaches, in a manner to be described in detail later on.

The front plate *h* of the watch work frame 90 has fixed thereto a curved spring arm *i*, which partially encircles the aforesaid toothed wheel *f* and which is fitted at its free extremity with a lateral finger *k* resting on the toothed circumference *g* of the wheel *f*. 95 A second curved spring arm *l* firmly attached to the front plate *h* and partially encircling the toothed wheel *f* from the other side, presses with its free extremity on the aforesaid spring arm *i*. A lateral finger *m* of 100 this spring arm *l* enters into the watch work and arrests or liberates the hammer *q* of the alarm device according to its elevation or position of height respectively. The alarm, if

an alarm clock of the ordinary kind is employed in the construction of the present time measuring device, may also be stopped in the customary manner by a nose *t* on the 5 rotary handle *p* engaging behind the hammer *q*.

Supposing the works of the watch and of the alarm to be wound up, the rotation of the minute hand *e* simultaneously rotates the 10 toothed wheel *f*, thereby causing the finger *k* of the spring arm *i* to ascend the inclines of the teeth *g* until it passes their apex, when it will fall into the adjacent incision and start its next ascent. In ascending the inclines of 15 the teeth *g* the spring arm *l*, resting with its free extremity on the spring arm *i*, as previously mentioned, is lifted and in consequence the lateral finger *m* of said spring arm *l* is raised off the rod *o* which is firmly attached to the anchor *n* of the hammer *q*. The alarm works, being now set free, oscillate the anchor *n* and the hammer *q* sounds an audible alarm in the well known manner until the lateral fingers *k* and *m* descend to their 20 former position. The instant of liberating the alarm device by the lateral arm *m* and the duration of the alarm signal may be varied according to desire or requirement. In Fig. 1 is shown in dotted lines the lateral arm 25 *m* arresting the rod *o* of the anchor *n* and preventing the latter from oscillation on its fulcrum under the driving impulse of the alarm works. About 10 to 20 seconds before the 3 minutes, assumed to be allowed as a time 30 unit for a conversation, elapse, the toothed wheel *f* raises the finger *k* of the spring arm *i* and with same the finger *m* of the spring arm *e* sufficiently to set free the anchor *n*. The alarm signal sounds in consequence during 35 10 to 20 seconds, calling the attention of the conversing party, of the telephone subscriber or of the attendant to the approaching end of the time unit. On continuing the conversation another alarm signal is sounded 40 at the end of the second time unit. During all the time the conversation is conducted the minute hand *e* moves along the graduation *b* on the dial plate *a*, permitting the duration of the conversation to be read off and 45 facilitating the calculation of the proper charge.

By providing an arrangement of well known kind, not illustrated in the drawing and requiring no detailed description, the 50 minute hand may be turned back to zero at the start of the conversation or it may automatically return to zero when the conversation is ended and when the works are stopped by hand.

60 In order to stop the works, when the time measuring device is not required for use, a rod *r* may be attached to the rotary handle *p*, said rod entering the works and terminating

near the balance ring *s*. By turning the handle *p* the rod *r* is brought to bear against 65 said balance ring *s* and in virtue thereof the works are stopped as will be readily understood.

To start the time measuring device hereinbefore described the handle *p* is turned laterally, thereby setting free the hammer *q* and the balance ring *s*, whereupon the driving impulse of the works acts upon the handle *e* and the toothed wheel *f* actuating the organs intermediate between the toothed wheel and 75 the alarm in the manner previously described.

While we have shown in the accompanying drawings the preferred form of our invention, it will be understood that we do not limit ourselves to the precise form shown, for many of the details may be changed in form or position without affecting the operativeness or utility of our invention, and we therefore reserve the right to make all such modifications as are included within the scope of the 80 following claims, or of mechanical equivalents to the structures set forth.

What we do claim as our invention, and desire to secure by Letters Patent, is:

1. Improved time indicator and alarm device of the nature set forth, comprising a minute hand driven around a minute-graduated dial plate, a wheel keyed to the shaft of the minute hand having incisions or teeth at 90 its periphery in accordance with the time intervals allowed as a unit for telephone conversations, an alarm device and means for actuating said alarm device by the aforesaid toothed wheel at the end of every time unit, 95 substantially as set forth.

2. Improved time indicator and alarm device of the nature set forth, comprising a minute hand driven around a minute-graduated dial plate, a wheel keyed to the shaft of 100 the minute hand having incisions or teeth at its periphery in accordance with the time intervals allowed as a unit for telephone conversations, a spring arm having a lateral finger resting on the serrated circumference of 105 the aforesaid wheel, a second spring arm pressing on the first spring arm and having a lateral finger, and an alarm device, whose actuating means are under the control of the lateral finger of the second spring arm, substantially as set forth.

3. Improved time indicator and alarm device of the nature set forth, comprising a minute hand *e* driven around the minute-graduations *b* of a dial plate *a*, a wheel *f* keyed to 110 the shaft *c* of the minute hand *e* behind the dial plate *a* having incisions or teeth *g* at its circumference, a spring arm *i* having a lateral finger *k* resting on the toothed periphery of the wheel *f*, a second spring arm *l* pressing 115 on the spring arm *i* having a lateral finger *m*,

an alarm driven by a spring work of the usual kind, an anchor *n* carrying the hammer *q* for sounding the alarm, and a rod *o* in attachment with the anchor *n*, said rod *o* being under the influence of the lateral finger *m*, substantially as set forth.

In witness whereof we have hereunto

signed our names this 31st of May 1906, in the presence of two subscribing witnesses.

JOHN ROUNSEVILL.

AUGUST BILMS.
